US00D507880S

(12) **United States Design Patent** (10) Patent No.: **US D507,880 S**
Hassell et al. (45) Date of Patent: **** Aug. 2, 2005**

(54) **CRATE FOR BOTTLES OR THE LIKE**

(75) Inventors: **Jon P. Hassell**, Atlanta, GA (US);
William P. Apps, Alpharetta, GA (US);
Gerald R. Koefelda, Rowlett, TX (US)

(73) Assignee: **Rehrig Pacific Company**, Los Angeles,
CA (US)

(**) Term: **14 Years**

(21) Appl. No.: **29/174,475**

(22) Filed: **Jan. 17, 2003**

(51) LOC (8) Cl. **03-01**

(52) U.S. Cl. **D3/313**

Primary Examiner—Louis S. Zarfus
Assistant Examiner—John Windmuller

(57) **CLAIM**

The ornamental design for a crate for bottles or the like, as shown and described.

DESCRIPTION

FIG. 1 is a perspective view of a first embodiment of the crate showing our new design;

FIG. 2 is a top plan view thereof at an enlarged scale;

FIG. 3 is a front elevational view thereof at an enlarged scale, the rear elevational view being a mirror image thereof; FIG. 4 is a left side elevational view thereof at an enlarged scale, the right side elevational view being a mirror image thereof;

FIG. 5 is a bottom plan view thereof at an enlarged scale;

FIG. 6 is a perspective view of a second embodiment of the crate showing our new design;

FIG. 7 is a top plan view thereof at an enlarged scale;

FIG. 8 is a front elevational view thereof at an enlarged scale, the rear elevational view being a mirror image thereof;

FIG. 9 is a left side elevational view thereof at an enlarged scale, the right side elevational view being a mirror image thereof; and,

FIG. 10 is a bottom plan view thereof at an enlarged scale.
